UNITED STATES PATENT OFFICE.

FRANK D. MERSEREAU, OF ORANGE, NEW JERSEY.

DESIGN FOR A HANDLE.

SPECIFICATION forming part of Design No. 18,528, dated August 14, 1888.

Application filed June 8, 1888. Serial No. 276,515. Term of patent 3½ years.

To all whom it may concern:

Be it known that I, FRANK D. MERSEREAU, a citizen of the United States, residing at Orange, in the county of Essex and State of New Jersey, have invented and produced a new and original Design for Handles for Cork-Screws or other Objects, of which the following is a specification, reference being had to the accompanying drawing, forming a part 10 thereof.

The leading feature of my design for a handle suitable for corkscrews is the handle, as shown, provided with enlarged rosette-like ends, and the surface of the whole being in a 15 roughened and uneven state, as shown.

The figure represents a perspective view of my newly-designed handle.

A represents the central portion of the handle, slightly enlarged or full about its center, 20 and has a slight depression surrounding the same, as shown.

B B are the ends enlarged, as shown in the drawing, and provided with ornamentation thereon, consisting of the surface being slightly raised, as shown at a. The entire surface is 25 slightly roughened or uneven, giving the appearance of wood with the bark left thereon.

I claim—

The design for a handle for a corkscrew, &c., as herein shown and described, the same 30 consisting of the central portion thereof slightly enlarged at its center, with a slight depression surrounding the same, the enlarged rosette-like ends, and the surface slightly roughened or uneven, as shown.

FRANK D. MERSEREAU.
